UNITED STATES PATENT OFFICE.

RAYMOND I. HILL, OF ELYRIA, OHIO.

COIN-CONTROLLED VENDING-MACHINE.

No. 899,979.

Specification of Letters Patent.

Patented Sept. 29, 1908.

Application filed December 20, 1906, Serial No. 348,801. Renewed June 3, 1908. Serial No. 436,469.

To all whom it may concern:

Be it known that I, RAYMOND I. HILL, a citizen of the United States, residing at Elyria, in the county of Lorain and State of Ohio, have invented certain new and useful Improvements in Coin-Controlled Vending-Machines, of which the following is a specification.

This invention relates to coin controlled vending machines and has in view a simple and practical machine of this character embodying means for conveniently vending such articles as matches, salted peanuts, cigars, and the like.

To this end the invention primarily contemplates a type of machine possessing special utility for conveniently selling a predetermined quantity of matches in bulk, although capable of general application for the handling and sale of any article that can be conveniently held in the magazine and delivered or discharged through the action of the discharging plunger of the machine.

A further object of the invention is to provide a simple and practical means of utilizing the coin as the coupling or connecting element between the operating slide and the discharging plunger of the machine, and also providing means whereby it is impossible to operate the machine except when a coin is properly positioned between the elements referred to.

Another object in this connection is to provide a construction wherein a coin is automatically released and ejected from its operative position on the return stroke of the operating slide.

With these and many other objects in view, which will more readily appear as the nature of the invention is better understood, the same consists in the novel construction, combination, and arrangement of parts hereinafter more fully described, illustrated, and claimed.

The essential features of the invention involved in carrying out the objects above indicated are necessarily susceptible to structural change without departing from the scope of the invention, a preferred embodiment of which is shown in the accompanying drawings, in which:

Figure 1 is a side view of a coin controlled vending machine embodying the present invention. Fig. 2 is a vertical central longitudinal sectional view of the same. Fig. 3 is an enlarged detail sectional view showing

the parts in their normal position and a coin introduced onto the coin holder of the operating slide. Fig. 4 is a similar view showing the operating slide and plunger lifted to a 60 position for discharging the vended articles through the delivery opening of the machine onto the receiving tray. Fig. 5 is a cross sectional view on the line 5—5 of Fig. 3, showing the position of the coin in dotted lines. 65

Like references designate corresponding parts in the several figures of the drawings.

In carrying out the present invention the machine case, designated in its entirety by the reference character C, essentially consists 70 of the opposite inclosing side walls 1—1, the front and rear end walls 2 and 3 respectively, and the top and bottom members 4 and 5 respectively. It is preferable in the construction of this machine case to make the 75 inclosing sides 1—1 of glass plates, thereby producing what may be termed a transparent case or box which exposes the entire contents thereof to view. The case C has arranged longitudinally therein an inclined 80 partition frame 6 supported at its front lower end upon frame leg members 7 resting on the bottom 5 of the case. This inclined partition frame 6 and the leg members 7 thereof are spaced a distance from the front wall 2 85 to provide an intervening vertically disposed slideway 8 within which registers and slides a vertically reciprocating discharging plunger 9, which will be presently more particularly referred to. Also, the said inclined par- 90

partition frame 6 supports thereon an inclined partition plate 10 constituting the main partition, which divides the interior of the machine case into a magazine compartment 11 and a lower money receptacle 12, the latter 95 being designed to receive and hold the used coins which may be removed from time to time through a door inclosed opening 13 arranged at any readily accessible point in the case. In addition to performing the func- 100

tion of a dividing partition, the said plate 10 acts in the capacity of a feeding table upon which is supported the matches in bulk, or other articles stored in the magazine compartment 11 to be vended from the machine. 105 By reason of the upward inclination of the table or plate 10 the articles have a tendency to gravitate toward the front wall 2 of the case and lie over and upon the inclined lifting head 14 provided at the top end of the plunger 9 and designed to lie flush with the plate 110 10, as a continuation thereof when the plun-

ger rests in its lowermost position. To provide for checking the feed of the articles onto the plunger head 14 there is preferably arranged within the front part of the magazine compartment 11 a pendent check plate 15. This plate is preferably secured to the outer side of the case top 4 and the lower end 16 of said plate lies above the feeding table or plate 10 a sufficient distance to leave a feed throat 17 of a size permitting only the proper number of articles to pass into the space above the plunger head 14, thereby holding back in the magazine compartment the main bulk or body of the articles to be vended.

15 The vertically reciprocating discharging plunger 9 is preferably of a hollow formation and may be conveniently constructed of sheet metal, but to secure effective action the said plunger is preferably co-extensive in length with the depth of the slideway 8 accommodating the same, and in its front wall is provided a longitudinally disposed clearance slot 18 accommodating therein the spaced supporting arms 19 projecting inwardly from a vertically reciprocating operating slide 20 and constituting the coin holder for the coin introduced into the machine for operating the same. The discharging plunger is provided at its lower end with 25 a closed bottom portion 21 constituting a coin tray having the bottom and side deflecting plates 22 and 23 respectively, said plates being downwardly inclined to provide for insuring the deflection of the coin through the 30 coin discharge opening 24 at the lower end and inner side of the plunger 9, and into the coin receptacle or compartment 12 below the table or partition 10.

35 The coin tray 21 constituting the bottom of the discharging plunger 9 is spaced from and lies below the plane of a fixed abutment lug 25 projected forwardly from the rear wall of the plunger 9 and adapted to overlie the coin holder of the operating slide in a plane 40 between the arms 19 constituting said coin holder. At this point it will be observed that in the vertical plane of the lug 25, the bottom deflecting plate 22 of the plunger coin tray is preferably formed at its front end 45 with an upturned rest finger 26 which supports and braces the coin at its under side when held in the coin holder 19-19 and drawn against the abutment lug 25 to provide for coupling or connecting the operating 50 slide of the discharging plunger. When the parts are thus connected the plunger head 14 is adapted to be lifted or drawn into the plane of the vertical delivery opening 27 provided in the front wall 2 of the case. Matches 55 or other articles which drop through the front delivery opening 27 are caught and held in the purchaser's receiving tray 28 fitted to the front wall of the case contiguous to and below the plane of the said opening 27.

60 In the upward movement of the connected

operating slide and discharging plunger, the held coin *c* is carried against an inwardly bowed ejecting spring 29 suitably fitted to the front part of the machine case and projecting through the front clearance slot 18 of the discharging plunger. As the coin is drawn against and onto the spring 29 the same is placed under compression so that immediately upon releasing the upward pull or pressure on the operating slide, and hence 70 releasing the clamping pressure upon the coin, the spring 29 is free to act and kick the coin off of its support and through the opening 24 into the money receptacle 12.

75 The vertically reciprocating operating 80 slide 20 is preferably mounted to work in an incased guideway 30 constructed within the front part of the machine case at the inner side of its front wall and extending from the bottom of the case to the plane of the delivery opening 27. The plate member 31 forming the inner wall of the guideway 30 is longitudinally slotted, as at 32, to correspond with the clearance slot 18 of the discharging plunger, and the front wall of the 85 machine case, which constitutes the front wall of the guideway 30, is also provided with a longitudinal play slot 33, which accommodates the play of the outwardly projecting pull knob or handle 34 rigidly fitted to the operating slide 20. The slide 20 is provided near its lower end with a coin slot 35 arranged in the horizontal plane of the coin holder 19-19 and adapted to register with a similar slot 36 formed in a shiftable 90 guard plate 37. This guard plate is slidably supported in front of the guideway 30 for the operating slide at the lower end of the machine case, and is arranged to have a limited vertical play over a holding screw 38 95 fitted to a fixed point of abutment, and projecting through the limiting slot 39 provided in the plate 37 above its coin slot 36. The plate 37 has projected therefrom a connecting stud 40 to which is connected one end of the retracting spring 41, the other end of 100 which is connected with the pull knob 34 or other fixed part of the operating slide 20. When the parts are in their lowered normal position, the coin slots 35 and 36 register 105 with each other and also with the main coin slot 42 of the machine case, so that a coin can be readily introduced to a position upon the arms 19 constituting the coin holder. After thus introducing the coin, the operating slide is lifted with the result of carrying 110 all parts to the position shown in Fig. 4 of the drawings. It will be observed that in this movement the guard plate 37 is moved a sufficient distance to carry its slot 36 above 115 the plane of the machine slot 42 and thereby close the machine against the introduction of the coin until all parts have returned to their normal position shown in Fig. 3.

120 From the foregoing it is thought that the 110

125 130

construction, operation, and many advantages of the herein described machine will be readily apparent without further description, but at this point, attention is directed to the fact that to assure certainty of operation, and the proper positioning of the coin, it is preferable to form the abutment lug, at what may be termed the back corner thereof, with a downwardly projecting stop projection *s* which acts in the capacity of an arresting stop to provide for arresting the inserted coin directly beneath the abutment 25 when the latter is down.

I claim:

1. In a machine of the class described, the case, a reciprocating plunger having a slide and provided at its bottom with a coin deflecting tray, and a reciprocating operating plunger having a coin holder lying above said tray and adapted to carry and hold the coin against a fixed part of the plunger.

2. In a machine of the class described, the case, a vertically reciprocating discharging plunger provided at the bottom with a coin deflecting tray, and a vertically reciprocating operating plunger having a coin holder adapted to be coupled with the discharging plunger by the coin.

3. In a machine of the class described, the case, a reciprocating discharging plunger provided at one end with a coin deflecting tray and above the plane of the latter with an

abutment lug, and an operating slide having a coin holder lying above said coin tray and a coin slot in the plane of said holder.

4. In a machine of the class described, the case, a reciprocating discharging plunger provided at its lower end with an abutment lug and below the plane of the latter with a coin deflecting tray having a centrally located upstanding coin rest, a reciprocating coin slide having a pull knob and provided with a coin slot and in the plane of the latter with a coin holder consisting of a pair of spaced supporting arms, a shiftable guard plate also having a coin slot and supported for limited vertical play at one side of the operating slide, and a reciprocating spring connection between the guard plate and a fixed part of the operating slide.

5. In a machine of the class described, the machine case, a vertically reciprocating discharging plunger provided at its lower end with an abutment and a coin deflecting tray, a reciprocating operating slide having a coin slot and a coin holder, and a fixedly positioned ejecting spring arranged in the path of the coin and carried by the coin holder.

In testimony whereof I hereunto affix my signature in the presence of two witnesses.

RAYMOND I. HILL.
